UNITED STATES PATENT OFFICE.

ANSON S. RICE AND LOUIS J. FULLER, OF BROOKLYN, NEW YORK, ASSIGNEES TO DU-
PARQUET, HUOT & MONEUSE COMPANY, A CORPORATION OF NEW YORK.

ELECTRIC HEATER.

Application filed February 1, 1923. Serial No. 616,386.

To all whom it may concern:

Be it known that we, ANSON S. RICE and LOUIS J. FULLER, both citizens of the United States, residing in Brooklyn, county of 5 Kings, State of New York, and whose post-office address is % Duparquet, Huot & Moneuse Company, 108-114 West 22nd Street, New York, New York, have invented certain new and useful Improvements in Electric 10 Heaters; and we do hereby declare the following to be a full, clear, and exact description of the invention, such as will enable others skilled in the art to which it appertains to make and use the same.

15 This invention relates to electric heaters in which a surface is conductively heated by adjacent resistance elements, and has for its object the provision of an improved structure whereby the surface is more uniformly 20 and effectively heated and whereby the construction of the heater is simplified.

This application is a continuation in part of our copending application, Serial No. 482,881, filed July 7, 1921.

25 It is well known to construct heaters by retaining heating elements in grooves formed in the metallic surface to be heated, called the surface plate, and this construction has been extensively used. The usual method 30 has been to embed the heater element in plastic cement, taking care that the element does not make contact with the plate at any point. This method, however, gives rise to many defective heaters, as it is extremely 35 difficult to maintain an even layer of cement between the element and the surface plate. Even though an electrical short circuit does not result, there is usually uneven heating of the plate surface because of the varying distances 40 between the heater coils and the plate to be heated, the plate being hottest where the thermal path is shortest. Further, a great amount of heat is dissipated in the insulating cement with attendant loss in the 45 amount of heat that reaches the surface plate and reduction in the efficiency of the heater.

The construction provided by the present invention eliminates these difficulties and results in a greatly improved heater. In accordance with this invention, the surface plate is provided with ribs which stand out from the surface preferably a distance greater than the heating element which is to be used. The heating element may be retained 50 in the grooves between these ribs, the ribs

serving to conduct the heat from the coils to the plate. In order that the element may be positively positioned, insulator channels, preferably of lava, are first laid in the grooves between the ribs, and the element is 60 then placed in the insulator channels. By this means the element may be evenly spaced from the metallic plate and its integral ribs and the possibility of contact between the element and the plate is eliminated. Because 65 the walls of the channels are of uniform thickness, the thermal path to the surface plate is substantially constant in all directions and the plate is accordingly uniformly heated.

70 Further advantages will appear from the accompanying drawings and following description, which disclose more in detail a preferred embodiment. In the drawings:

75 Fig. 1 is a vertical section through a completely assembled heater.

Fig. 2 illustrates one of the insulator channels used to space the heating element from the plate.

80 Figs. 3 and 4 illustrate two of the operations in assembling the heater.

85 Fig. 5 is a bottom view of a completely assembled heater with portions cut away to show the internal construction.

90 Referring now to these drawings, the surface plate 1 is provided at one side with a series of ribs 2 and a continuous flange 3, of greater height than the ribs, extending completely around the plate. The ribs 2 may be arranged in any convenient manner, the arrangement illustrated in Fig. 5 being preferred, as it provides a continuous groove in which the heater coils 4 may be laid. One 95 of the insulator channels 5 which are used to space and insulate the coils 4 from the surface plate 1 and its ribs 2, is clearly illustrated in Fig. 2. It will be seen that this channel is adapted to enclose the coil on three sides, and that the wall thickness is very nearly uniform. This insures the coil 100 being positioned in the grooves between the ribs 2 so that the thermal paths to the plate or its ribs are equal in all directions. This channel is preferably formed of lava which is highly refractory and yet has a high conductivity as compared with insulating cements and the like. As shown in Fig. 2 the insulator channels are separately or previously formed and bodily laid in the spaces 105 between the ribs, hence they may be made 110

with sufficient accuracy to obtain a uniform thickness of the walls. The heating element 4 used in this heater consists of helically wound coils of resistance wire, and may be connected in any convenient manner to a source of electricity through binding posts 6.

The heater plate may be conveniently assembled by inverting it, as in Fig. 3, and placing the insulator channels 5 in the grooves between the ribs 2 and then laying the resistance coils 4 in the channels, as shown in Fig. 4. In order to retain the channels and coils in place, insulating cement 7 may be packed in to a depth sufficient to cover the ribs 2. A second layer of insulation, which is preferably of extremely low heat conductivity, may now be placed on top of the cement 7 in order to direct as much heat as possible to the surface plate. In order to insure a rigid structure and prevent breakage of the insulating cement, a metal cover plate 9 is securely fastened to the flange 3 of the surface plate.

It is to be understood that this disclosure of a preferred embodiment is not to be construed as a limitation of this invention, as it is clear that the improved construction is applicable to many heating devices and may be considerably modified or adapted without departing from the spirit or scope of the invention.

I claim:

1. An electric heater comprising a surface plate to be heated having metal ribs extending therefrom, lava channels disposed between said ribs, and a heating element disposed in said insulator channels, said channels serving to insulate said heating element from said plate and ribs.
2. An electric heater comprising a surface plate having ribs extending therefrom and integral therewith, separately formed insulator channels of substantially constant wall thickness disposed between said ribs, and a heating element disposed in said channels, said channels serving to position said wire equidistant from said plate surface and said adjacent ribs.
3. An electric heater comprising a surface plate having a continuous flange adjacent its perimeter and ribs extending therefrom to form grooves, separately

formed insulator channels of substantially constant wall thickness disposed between said ribs, a heating element disposed in said channels, said channels and heating element being retained by insulating material, and a cover plate attached to said flange to retain said insulating material, said channels serving to insulate said heating element from said surface plate and position said heating element equidistant from said plate and said adjacent ribs.

4. The combination with a heater plate having ribs extending therefrom to form troughs, of a heating element positioned between said ribs and lava channels partially surrounding said coils, said channels serving to insulate said coils from said ribs and plate and to position said coils from said ribs a distance substantially equal to the distance from said surface plate to said heating element.

5. An electric heater comprising a surface plate having ribs extending therefrom and integral therewith, separately formed insulator channels of substantially constant wall thickness disposed between said ribs, a heating element disposed in said channels, said channels serving to position said wire equidistant from said plate surface and said adjacent ribs, insulating cement covering said coils and said channels, and a cover plate attached to said surface plate to retain said insulating cement.

6. An electric heater comprising a surface plate having metal ribs extending therefrom, a heating element disposed between said ribs, lava channels surrounding said coils on three sides, and cement covering the coils on the remaining side, said cement serving to retain said coils and channels between said ribs.

7. An electric heater comprising a surface plate having ribs extending therefrom, a heating element located between said ribs, and lava located between the heating element and the adjacent ribs and surface plate.

In testimony whereof we affix our signatures.

ANSON S. RICE.
LOUIS J. FULLER.
